UNITED STATES PATENT OFFICE.

CHARLES LOEFFLER, OF PHILADELPHIA, PENNSYLVANIA.

ELECTRIC FIRE-ENGINE SYSTEM.

1,160,422.

Specification of Letters Patent. Patented Nov. 16, 1915.

Application filed November 16, 1914. Serial No. 872,503.

To all whom it may concern:

Be it known that I, CHARLES LOEFFLER, a citizen of the United States, residing at Philadelphia, in the county of Philadelphia, and State of Pennsylvania, have invented

5 certain new and useful Improvements in Electric Fire-Engine Systems, of which the following is a specification.

My invention relates to improvements in

10 electric fire engine systems, the object of the invention being to provide a fire engine supporting an electric motor for operating the pump, and provide an improved system of electric distribution, whereby the electric

15 current from the system can be utilized only when the valve controlling the water plug is opened.

A further object is to provide an improved electric control located within the ordinary water plug, the movement of the valve of the plug to closed position causing the opening of the electric circuit, and the movement of the valve to open position causing the closing of the electric circuit, so that the current may be utilized for driving the motor of the engine and cannot be used for any purpose except when the water is turned on, thereby preventing fraudulent use of the electric current, and also preventing accidental electric shock.

With these and other objects in view, the invention consists in certain novel features of construction and combinations and arrangements of parts as will be more fully hereinafter described and pointed out in the claims.

In the accompanying drawings, Figure 1 is a view in elevation illustrating my improved fire engine showing the same connected to the water plug. Fig. 2 is a view in transverse section through the hose connecting the plug with the pump of the engine. Fig. 3 is a view in vertical longitudinal section through the water plug. Fig. 4 is a view in vertical section on an enlarged scale on the line 4-4 of Fig. 3. Fig. 5 is a view in section on the line 5-5 of Fig. 3 showing a portion of the casing broken away, and Fig. 6 is an electric diagram.

1 represents a wheeled vehicle which preferably comprises an automobile, but my invention is not limited to the particular vehicle employed, as I may use my improvements in connection with other styles of vehicle as well. The vehicle 1 supports a pump 2 driven by an electric motor 3.

4 is a hose connecting the pump with the ordinary water plug 5; and 6 is a hose connected to the discharge side of the pump and adapted to direct the water onto the fire.

The plug 5 may be of any suitable construction such as commonly employed for use in case of fire. In the drawings I have illustrated a plug in which the water is directed through a pipe 7 to a discharge outlet 8, the latter normally closed by a removable screw-threaded cap 9.

A valve 10 controls the flow of water, and is connected to a rotary stem 11, the latter having a screw-threaded portion 12

70 engaging internal threads in a sleeve 13, so that when the stem is turned, the valve 10 is caused to raise and lower.

The stem 11 is made angular at its upper end as shown at 14 for the reception of a crank arm 15 or wrench to turn the same. The plug in its upper portion is formed with a chamber 16 which is entirely cut off from the water, and in which chamber I locate my improved electric contacts 17, 17. These contacts 17, 17 are pivotally supported at their upper ends on pins 18 located in a box 19, the latter secured to the inner face of the water plug 5.

The pins 18 are preferably inclosed by insulating sleeves 20, so that the contacts 17 are thoroughly insulated from their supports and from each other. The lower ends of the contacts 17 are flared apart as shown at 21, and coiled springs 22 bear against the contacts and tend always to press them together.

23 is a lever composed of non-conducting material which is pivotally supported between its ends on a depending lug 24, integral with a laterally projecting arm 25 on box 19. A coiled spring 26 is located at the outer end of the arm 25, and exerts a downward pressure on the end of the lever 23 tending always to press one end of the lever between the contacts 17 and separate the latter to open the electric circuit as will be hereinafter explained. To facilitate the entrance of the lever 23 between the contacts, the upper face of said lever at its ends is beveled as shown at 29, so that it readily finds an entrance between the flared ends of the contacts.

On the stem 11, a collar 30 is fixed, and this collar engages one end of the lever 23 when the stem is moved upwardly to open valve 10. This upward movement of the

stem 11 causes the lever 23 to fulcrum and to move downwardly from its position between the contacts 17, allowing springs 22 to move the contacts together. When the 5 stem 11 is moved downwardly to close the valve 10, the spring 26 will return the lever 23 to its position between the contacts 17 as clearly shown.

31 represents an electric conduit containing two line wires 32 and 33. A wire 34 connects the wire 33 with one of the contacts 17. A second wire 35 connects the other contact 17 with a terminal contact 36 located in a terminal socket 37 on the outside of the wa- 15 ter plug 5.

A wire 38 connects the line wire 32 with the other contact 39 in the terminal socket 37. The hose 4 which connects the water plug 5 with the motor 2 is preferably pro- 20 vided with a strip 40 of canvas inclosing a flexible tube 41 containing two electric wires connected to the motor 2.

At one end of the flexible tube 41, a plug 42 is provided which is adapted to be positioned in the terminal socket 37 and connect the contacts in the socket with the electric motor. The other end of the tube 41 is also provided with a plug 43 to enter a socket 44 connected to the electric motor 3.

30 The hose 4 is provided at its ends with ordinary pipe couplings 45, so that it can be readily connected to the pump and to the plug. It will be noted that with my im- 35 proved arrangement of parts, that when the valve 10 is closed, the electric circuit to the contacts 36 and 39 of the terminal socket 37 is open, and no current can be used either through accident or design.

When the engine arrives and connects the 40 pump 2 with the plug 5 by means of the hose 4, and also makes the necessary electrical connections, the upward movement of the valve 10 by means of the stem 11 will cause the operation of the lever 23 to permit the 45 contacts 17 to move together and close the circuit, so that a supply of electricity may be had to the motor to drive the pump. As soon as the water is shut off, the circuit will be automatically broken, so that there will 50 be no waste of current.

In Fig. 6, I show an electric diagram illustrating how a number of plugs may be connected to the same line wires, and with my improved system, this plan may be car- 55 ried out for any number of plugs.

Various slight changes might be made in the general form and arrangement of parts described without departing from my in- 60 vention, and hence I do not limit myself to the precise details set forth, but consider

myself at liberty to make such changes and alterations as fairly fall within the spirit and scope of the appended claims.

Having thus described my invention, what I claim as new and desire to secure by Letters Patent is:

1. In an apparatus of the character de- 70 scribed, a water plug having means thereon for the attachment of a hose, and having pivoted terminal spring-pressed electric contacts closing an electric circuit when together, a vertically movable valve stem, and a lever of insulating material normally spring-pressed into position between the contacts to open the circuit, and movable by the 75 stem out of position between the contacts when the stem moves in a direction to allow a flow of water through the plug, substan- tially as described.

2. In an apparatus of the character de- 80 scribed, a water plug having means thereon for the attachment of a hose, and having terminal electric contacts, a valve in the wa- 85 ter plug controlling the flow of water there- through, spring-pressed contacts in the plug connected to the terminal contacts, and in- cluded in circuit with a source of electricity, a stem on said valve movable longitudinally to open and close the valve, and a lever of 90 non-conducting material controlled by the stem and adapted to separate the contacts when the valve is closed, substantially as de- scribed.

3. In an apparatus of the character de- 95 scribed, a water plug having means thereon for the attachment of a hose, and having terminal electric contacts, a valve in the wa- 100 ter plug controlling the flow of water there- through, spring-pressed contacts in the plug connected to the terminal contacts, and in- cluded in circuit with a source of electricity, a stem on said valve movable longitudinally to open and close the valve, a lever of non- 105 conducting material pivotally supported be- 110 tween its ends, a spring exerting pressure on the lever and normally holding the same between the said contacts, separating the latter, and a collar on the valve stem engaging the lever and adapted when the stem is moved in a direction to open the valve to move said lever from between the contacts, substantially as described.

In testimony whereof I have signed my name to this specification in the presence of two subscribing witnesses.

CHARLES LOEFFLER.
